ATTYS.

UNITED STATES PATENT OFFICE.

FRANK WESLEY BULL, OF OSHAWA, ONTARIO, CANADA.

PLAYER-PIANO.

1,344,984.

Specification of Letters Patent. Patented June 29, 1920.

Application filed January 27, 1920. Serial No. 354,389.

To all whom it may concern:

Be it known that I, FRANK WESLEY BULL, a subject of the King of Great Britain, residing at Oshawa, in the county of Ontario, 5 in the Province of Ontario, Canada, have invented certain new and useful Improvements in Player-Pianos, of which the following is the specification.

My invention relates to improvements in 10 player pianos, and the object of the invention is to devise means for teaching a person who has no knowledge of music to play any piece which is played by the player piano by enabling the operator to readily 15 read the notes of the tune sheet as represented by the perforations therein, and it consists essentially of the arrangement and construction of parts as hereinafter more particularly explained.

20 Figure 1 is a front elevation of a portion of a player piano showing the tracker bar, tune sheet, supporting rollers, and my device applied thereto.

Fig. 2 is an enlarged sectional view 25 through Fig. 1.

Fig. 3 is a plan view of my miniature key board broken away intermediate its length.

Fig. 4 is a cross sectional view on line 4—4 Fig. 2.

30 Fig. 5 is a cross sectional view on line 5—5 Fig. 2.

In the drawings like characters of reference indicate corresponding parts in each figure.

35 1 indicates the outer casing of the player piano provided with the usual rectangular orifice 2. 3 and 4 indicate the ends in which the tune sheet supporting rollers 5 and 6 are mounted in the usual manner. 7 indicates

40 a tracker bar provided with the usual note orifices 10. The tune sheet 7 is provided with the usual note perforations 11 and is operated so as to travel from the roller 5 to the roller 6. 12 is a curved bar which is

45 rigidly secured by screws 13 to each end 3 and 4 the center of the curved bar being approximately opposite the center of the tracker bar. 14 is a similarly curved bar extending parallel to each bar 12 and spaced

50 apart therefrom. 15 is a miniature key board-chart which is provided at each end with a reduced portion 16 slidable between the bars 12 and 14. Each bar 14 in proximity to its end is provided with an orifice 18. 19 is a screw which passes freely through

55 each orifice 18 and is secured in the bar 12.

The screw 19 is preferably provided with a washer 20 bearing against the under face of the head of the screw 19 and 21 is a compression spring extending between the 60 washer and the bar 14. By this means the bars 12 and 14 are resiliently held together thereby permitting perfect freedom of movement of the miniature key board-chart and enabling it to be readily slid up or down to 65 the required position.

It will be understood that the notes of the miniature key board-chart are of such size that each note is directly opposite a longitudinal line of perforations in the tune 70 sheet. When the operator desires to read any of the notes reproduced by the perforations of the tune sheet he slides the miniature key board-chart 15 from the position shown by full lines in Fig. 2 to the position 75 shown by dotted lines in the same figure. By this means he brings the notes represented on the miniature key board-chart in line with the note perforations of the tune sheet and this will readily indicate to him 80 what notes these perforations represent. If desired the miniature key board-chart may have the flats and sharps and naturals indicated above each note and also the miniature key board-chart may be divided into octaves and the key board-chart of the piano may be similarly divided so as to enable him to readily see where the notes are located on the key board enabling him to immediately place his fingers in position upon the 85 notes. The operator may bring any portion of the tune sheet to the exposed position and by the method above described memorize the notes which comprise the corresponding portion of the music. The tune sheet may 90 then be turned to expose the next portion or if desired a portion of music may be played on the player piano so as to help the operator to obtain the rhythm of the music and the proper expression.

100 From this description it will be understood that I have devised a very simple device which will readily teach a person who has absolutely no knowledge of music how to play a piece, and which result may be 105 accomplished in a very short time not only teaching the operator the notes he is to play but also enabling him to play them to get the desired melody.

110 What I claim as my invention is:

1. In a player piano provided with the usual perforated tune sheet, a key board-

chart, and means for supporting the key board so as to be slidable in a downward direction when in a horizontal position in front of the tune sheet with each note there-
5 of opposite the path of one horizontal row of note perforations.

2. In a player piano provided with the usual perforated tune sheet, a guide way supported at each end of the tune sheet, and
10 a miniature key board-chart slidably held at its ends within the guide way and having a note thereof opposite a longitudinal line of perforations of the tune sheet.

3. In a player piano provided with the usual tune sheet, a guide way located at each end of the tune sheet each comprising a bar secured to the gable of the spool box, a bar parallel to each of the aforesaid bars

and resiliently connected thereto, and a miniature key board slidably held at its ends between each pair of stationary and resiliently held bars.

4. In a player piano provided with the usual tune sheet, a guide way located at each end of the tune sheet each comprising a bar secured to the gable of the spool box, a bar parallel to each of the aforesaid bars and resiliently connected thereto, a miniature key board-chart slidably held at its ends between each pair of stationary and resiliently held bars, and a key board-chart having reduced ends fitting between the stationary and resiliently held bars so as to be slidable therebetween.

FRANK WESLEY BULL.
